PAINT BRUSHES

Harold H. Schwartz, Port Chester, and Jean S. Tucker, White Plains, N. Y., assignors to Empire Brushes, Inc., Port Chester, N. Y., a corporation of New York

Application December 31, 1952, Serial No. 329,006

2 Claims. (Cl. 15—192)

This invention relates to a brush for applying a liquid to a surface. It is more particularly directed to a brush of the latex emulsion type, commonly called a water paint brush.

The particular embodiment of the present invention, which is illustrated in the drawings, and which will be described hereinafter in greater detail, comprises generally, a brush back, and a plurality of knots of relatively fine gauge monofilament bristles extending outwardly from the brush back and converging toward each other.

It is a principal object of the present invention to provide a brush of the type described having a highly improved knot securing means, which includes means for excluding moisture from the brush back.

It is another object of the present invention to provide a paint brush employing crimped monofilament bristles of fine diameter, so that the brush will pick up and retain a good paint load, and the paint will not run up and down the bristles.

It is another object of the present invention to provide a brush of the type described in which the bristles of each knot are selected of different lengths according to a predetermined proportion. The proper proportions of various lengths of bristles will combine to produce excellent spreading of paint when applied, and the absence of coarse bristles will prevent brush marks or streaking of the paint. In addition, the brush is easily washed out as the monofilaments absorb a negligible amount of water.

As the knots are inclined inwardly, there will be no tendency of the bristles to flare, and the brush may be used within a well defined area. Furthermore, the crimped bristles tend to merge which minimizes spreading of the bristles and prevents fingering.

It is a further object of the present invention to provide a brush of the type described in which the individual knots are secured to the brush head by individual staples receiving the knot and extending into the brush back. Heretofore it has been common practice to insert a plug into the brush back for holding a knot in position. The plugs were subject to swelling upon absorbing moisture, sometimes cracking the brush back or the plug itself. This action of the brush back and plug resulted in loosening of the bristles, so that the bristles would flare outwardly or fall out of the brush back. By the present invention, the plug is eliminated and a waterproof glue covers the brush back to prevent the absorption of moisture.

The knot securing means of the present invention provides well defined spaces between the knots adjacent the brush back, and good density of bristles at the free ends thereof. The spaces between the knots, adjacent the brush back, form wells for holding a great quantity of paint for feeding the latter to the free end of the bristles. The high density of bristles at the paint end of the brush provides a smooth and even spreading, so that the paint retained by the brush will cover a maximum area, and dipping of the brush will be minimized.

2

It is yet a further object of the present invention to provide brush of the type described in which the bristle ends are roughened and tapered to better hold and spread paint. The roughened and tapered bristle ends act in the manner of a plurality of bristles and, being invisible to the naked eye, such roughening and tapering will help to eliminate brush marks.

It is a further object of the present invention to provide a brush of the types described which is simple and durable, effective for its intended purposes, and which can be manufactured and sold at a reasonable cost.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawing, in which is shown various illustrative embodiments of this invention:

Fig. 1 is a front elevational view of a brush constructed in accordance with the present invention;

Fig. 2 is a side elevational view of the device of Fig. 1;

Fig. 3 is an enlarged fragmentary sectional view taken on the line 3—3 of Fig. 1;

Fig. 4 is an enlarged view of the crimped monofilament bristles; and

Fig. 5 is a highly magnified view of the free end of a roughened bristle.

Referring now more particularly to the drawing, 10 designates generally a brush employing the present invention. The brush comprises a handle 11, a brush back on one end of the handle, and a plurality of knots of bristles 13 extending outwardly from the brush back. 35 The brush back 12 is formed of an elongated solid body 14 having an inner face 15 and an outer face 16, and having its ends rounded as at 17 and 18. The handle 11 projects from the inner face 15. The outer face 16 is formed with a plurality of transverse rows of cylindrical sockets or inwardly extending openings, best seen in Fig. 3, where there is shown a section through a transverse row of the openings.

Centrally of the face 16 are a pair of transversely spaced openings 20 and 21 which extend inwardly from the face 16 at right angles thereto and terminate in end walls 22 and 23, respectively. The end walls are spaced from the inner face 15 of the brush back. Outwardly of and spaced transversely from the openings 20 and 21 are openings 24 and 25, which extend inwardly through the face 16 and terminate in end walls 26 and 27. The openings 24 and 25 are each inclined at an angle of three degrees toward the openings 20 and 21 from their end walls 26 and 27 to the face 16. Adjacent to and spaced outwardly from the openings 24 and 25 are openings 28 and 29, which extend inwardly from the face 16 and terminate in end walls 30 and 31. The openings 28 and 29 are inclined inwardly toward the openings 20 and 21 at an angle of six degrees from the end walls 30 to the outer face 16.

A knot 50 of monofilament bristles is selected of various lengths in the desired proportions, and the knot is crimped to render the individual bristles zig zag in configuration, as seen in Fig. 4. Thus, each bristle, generally designated 40, is composed of a plurality of substantially straight portions such as 41 and 42 at an angle with respect to each other. The individual filaments are of uniform diameter, and the filaments of a particular knot are selected of the same diameter or gauge. It has been found preferable to employ filaments fabricated of polystyrene or copolymers thereof. It will be noted that the configura-

tion of the individual filaments causes the filaments to merge and minimize flaring or spreading.

When a knot of filaments has been selected and crimped, it is folded about its mid-portion and inserted into one of the previously described openings in the brush back. The knot 50 has its folded mid-portion inserted into the opening 28, and a U-shaped fastener or staple 51 has its bight portion receiving the mid-portion of the knot 50 and its legs extending through the end wall 30 into the brush back 14.

Thus, it is seen that every filament of the knot is secured within the brush back by a simple stapling operation. In order to waterproof the brush back and further secure the bristles within the openings, the openings are filled with glue as at 52. Sufficient glue is used to fill all the unoccupied space in the openings and overflow onto the face 16 as at 53. This procedure is employed for every opening and knot. In practice, the openings are filled prior to the insertion of the knot and the glue caused to ooze out of the openings. In either case, the glue fills the openings and covers the outer surface 16 to provide a waterproofing layer and prevent moisture from entering the openings.

When all the openings have been filled with knots of bristles, it will be seen that the bristles will converge outwardly such that the outer edge 55 of the bristles is narrower than the brush back. This will facilitate the painting of moldings and other narrow pieces.

The free end of the filaments are roughened and tapered by positioning the brush at an angle with respect to a moving abrasive, such as, sandpaper, and with its bristles engaging the abrasive. This will cause the ends of the bristles to be roughened and tapered, in which condition they hold more paint, and act as a plurality of microscopic filaments to help eliminate brush marks. It is preferred to dispose the brush at a forty-five degree angle with respect to a sandpaper surface and lubricate the sandpaper with water during the operation.

In view of the foregoing, it is seen that a paint brush is provided which has a high paint load capacity, which dispenses the paint in a smooth and even manner, and which is adapted for long continued and reliable use.

It is further seen that the present invention achieves its intended objects, and provides a paint brush which eliminates flaring bristles, and in which the bristles are securely held in the brush back.

It will thus be seen that there is provided a device in which the several objects of this invention are achieved and which is well adapted to meet the conditions of practical use.

As various possible embodiments might be made of the

above invention, and as various changes might be made in the embodiment above set forth, it is to be understood that all matter herein set forth or shown in the accompanying drawing is to be interpreted as illustrative and not in a limiting sense.

Having thus described our invention, we claim as new and desire to secure by Letters Patent:

1. A brush comprising an elongated backing member having a plane outer face, said backing member being provided with a plurality of longitudinally spaced transverse rows of cylindrical sockets, the said sockets in each transverse row comprising a pair thereof adjacent the longitudinal central plane of the backing member whose axes are normal to said plane outer face, a second pair of sockets one of which is disposed laterally outwardly of each of said first sockets and whose axes converge outwardly toward and are disposed at angles of substantially 3° to the axes of said first pair of sockets, and a third pair of sockets one of which is disposed laterally outwardly of each of said second sockets and whose axes converge outwardly toward and are disposed at angles of substantially 6° to the axes of said first pair of sockets, and a bundle of bristles having a butt end disposed in each of said sockets with the two inner longitudinal rows thereof projecting from said backing member normal to said plane outer face, and the outer longitudinal rows thereof projecting from said backing member and converging toward the said two inner longitudinal rows with the free ends of the bristles in substantial contact laterally of said backing member.
2. A brush according to claim 1 wherein each bundle of bristles is folded intermediate its ends providing a bight which is disposed in a respective socket, a staple engaged within the bight and driven into said backing member, said sockets being of greater diameter than the transverse dimensions of said bristle bights, and the spaces in said sockets surrounding said bristle bights being filled with glue which extends through the bights of the staples and the said plane outer face of said backing member being provided with a coating of glue intermediate said bristles and adhesively engaged therewith.
